UNITED STATES PATENT OFFICE.

EDWARD LANZONE, OF SOUTH RIVER, NEW JERSEY.

KILN.

SPECIFICATION forming part of Letters Patent No. 627,343, dated June 20, 1899.

Application filed June 2, 1898. Serial No. 682,397. (No model.)

To all whom it may concern:

Be it known that I, EDWARD LANZONE, a subject of the King of Italy, residing at South River, Middlesex county, New Jersey, have 5 invented certain new and useful Improvements in Kilns, of which the following is a specification.

This invention relates to improvements in kilns for burning pottery and other wares with 10 either an upward or downward draft; and the object is to produce a substantially even or uniform burning of the contents of the kiln throughout all its parts.

With the kilns now in use, so far as known, 15 and particularly those where the draft is downward through the wares being burned, there is great irregularity in the heat at different parts of the kiln, due to the heated gases taking certain defined paths down to 20 the main flue below, thus producing overburned and underburned areas or zones in the wares or materials, and the construction in which the present invention is embodied provides a novel form of bottom and floor for 25 the kiln, having in view the more equal distribution of the hot gases throughout all parts of the kiln as the said gases pass through the wares to be burned on their way to the chimney or uptake.

30 In the accompanying drawings the invention is shown as embodied in a kiln with a down draft.

Figure 1 is a horizontal section of the kiln, showing the floor-flues as they appear in plan, 35 before the floor-bricks are laid. Fig. 2 is a vertical cross-section of the kiln in the plane indicated by line x^2 in Figs. 3 and 4. Fig. 3 is a horizontal section taken substantially at line x^3 in Fig. 2. Fig. 4 is a fragmentary 40 plan, on a larger scale than the principal views, of a part of the bottom of the kiln at the center, showing only a part of the floor-bricks in place. Fig. 5 is a fragmentary sectional view on a larger scale, showing the central portion of the bottom, seen also in Fig. 2. Fig. 6 is a perspective view of the floor-brick 45 6 on a relatively large scale.

In a general way the body of the kiln is of an ordinary or known construction. It is circular in plan, has a concave ceiling, and is

provided with a plurality of equally-spaced furnaces F , formed in its outer wall W . The hot gases from the several furnaces enter an annular flue v in common with all the furnaces, rise in said flue, and pass over the top 55 of an inner circular wall w into the chamber of the kiln. On starting the fires the hot gases and smoke are or may be permitted to pass off through outlets o in the roof of the kiln, these outlets being afterward covered 60 or closed, so that the gases must then pass down through apertures in the floor to a flue or flues below, and thence to the chimney.

The above features are not new in kilns for 65 burning ceramic wares; but the construction of the floor and bottom of the kiln, in which the present invention is embodied, will now be described.

Below the floor of the kiln is a flue 1 to 70 carry off the gases to the chimney. As here shown, this flue extends entirely across the kiln diametrically, one end leading to the chimney and the other being closed in some manner to afford access thereto when necessary for cleaning the flue from time to time; 75 but it is only essential to the operation of the kiln that this flue shall extend to the center of the circular floor of the kiln, at which point it connects by a central down flue or passage 2 with a series of floor-flues under the floor- 80 bricks.

The circular floor of the furnace is divided into four quadrants, Fig. 1, by four radial main floor-flues 3, which connect tangentially at the center with the cylindrical flue 2, and 85 in each quadrant are numerous floor-flues 4, which are parallel with each other and with the main tangential floor-flue 3 of that quadrant. Thus the flues 4 lead into the main floor-flue 3 of the adjacent quadrant, meeting the latter at right angles, as clearly shown. The flues 3 and 4 are formed by and separated by dividing-walls of brick or tiles, and the four radial division-walls bridge the down-flue 2 by cross-arches 5, as shown in the several views. The bottoms of the main floor-flues 3 are sloped downward toward the central flue 2, as seen at the right in Fig. 2, for the purpose of gradually enlarging the cross-section of the flue toward the gas-delivering 90 95 100

point and to afford convenience in cleaning them of dust and ashes, which latter are swept to the main flue 1.

The floor proper of the kiln is formed of 5 apertured bricks 6, laid over the floor-flues and supported on the dividing-walls between them, as clearly shown, especially in Figs. 3 and 4. Each of the bricks 6 is of such a length as to extend over the floor-flue and to 10 the center line of the wall on which it is supported, and it has a recess formed in its vertical edge which when the bricks are placed together, as seen best in Fig. 4, produces an aperture 7, there being thus an aperture at 15 each floor-brick 6 for the passage of the hot gases down to the flues.

Obviously the floor-bricks may be renewed at any time wholly or in part, and access to the floor-flues at any point may be had by 20 moving the floor-bricks at that point.

The construction described will cause the uniform heating of the kiln, as each quadrant will be heated equally and every part of each quadrant will also be heated with substantial 25 uniformity, as there are practically no short and long roads for the gases to traverse, entering, as they do, from the periphery and passing off at the center.

Owing to the smallness of the scale of Fig. 30 3, the recesses 7 have not been represented therein; but they are clearly shown in Fig. 4 and the brick 6 on a large scale in Fig. 6.

The gases arising from the furnaces F through the annular flue v will be composed 35 in some degree of carbonic oxid, carrying free carbon in the form of smoke, and in order to attain more perfect combustion air-flues a are or may be formed in the side walls W, one above each furnace F by preference, to admit 40 air to the flue v to combine with the carbonic oxid and carbon, and to heat the air so admitted, and thus adapt it for combination without chilling the gases, the flue a has im- 45 parted to it a loop-like or inverted-U form, as clearly shown. The wall W will be more or less heated, especially at its inner surface, and the flue a is made to extend in, then upwardly, then in again to near the inner surface of the wall W, then downwardly, and 50 then into the flue v. Being directly over the crown of the furnace, the heat therefrom will also be utilized in heating the air as it flows through the flue a.

The radial flues 3 are herein shown as dividing 55 the bottom of the kiln into quadrants or quarters; but the invention is not limited to this number of radial flues and sections. There should be not less than three sections, however, and it is not advisable to have more 60 than six.

In Figs. 1 and 3, E represents the usual entrance to the kiln.

The bricks or tiles 6 may of course have

apertures in them; but it is more convenient to form the apertures in the floor by the recesses 7 in the bricks. 65

Where the floor-bricks 6 bridge over the main floor-flues 3, they will be supported at one end on a row of supporting bricks or tiles 8. (Best seen in Figs. 4 and 5.) The walls 70 between the flues 4 are recessed at their ends to receive the bricks 8 and bring their top surfaces down flush. These recesses are indicated in the plan, Fig. 4, which represents the central part of the kiln-floor denuded of 75 floor-bricks.

It will readily be seen that my construction has these characteristics: The hot gases descending from the top of the kiln through the wares pass down through the floor-apertures 80 at all points to the flues below. The conditions in all the quadrants or sectors of the floor are exactly alike—that is, the conditions of draft and temperature at any point in one quadrant will be exactly repeated in every 85 other quadrant. In each quadrant it will be noted that as the distance increases from the central down-flue 2 along a radial flue 3 to the point where a flue 4 enters it the said flue 4 will be correspondingly shorter to compensate, thereby equalizing to a good degree the travel of the gases. 90

Having thus described my invention, I claim—

1. A circular downdraft-kiln having a plurality of furnaces about it connected each with an inner, upright flue for the gases, a main outlet-flue 1, a central down-flue 2, leading into the flue 1, principal radial floor-flues 3, connecting tangentially with the down-flue 100 2, and dividing the floor of the kiln into equal sections, the flues 4, in each floor-section, parallel with each other and with one of the flues 3 and communicating with the next adjacent flue 3, and the apertured floor 105 of the kiln over said flues, substantially as set forth.

2. A circular downdraft-kiln having a plurality of furnaces about it, an annular inner flue v for said furnaces, an apertured floor, 110 radial main flues under the floor connecting tangentially with a central, cylindrical down-flue, said radial flues dividing the floor into quadrants, the shallower, parallel flues 4 in each quadrant, as shown, the main flue 1, 115 and the said down-flue at the center of the kiln connecting with the main flue below, substantially as set forth.

In witness whereof I have hereunto signed my name, this 30th day of April, 1898, in the 120 presence of two subscribing witnesses.

EDWARD LANZONE.
